(57) **CLAIM**

The ornamental design for an article handling device, as shown and described.

DESCRIPTION

A portion of the disclosure of this patent document contains material which is subject to copyright protection. The copyright owner has no objection to the facsimile reproduction by anyone of the patent disclosure, as it appears in the Patent and Trademark Office patent files or records, but otherwise reserves all copyright rights whatsoever.

FIG. 1 is a right side elevation view of an article handling device.

FIG. 2 is a bottom view of the article handling device.

FIG. 3 is a front elevation view of the article handling device.

FIG. 4 is a top view of the article handling device.

FIG. 5 is a left side elevation view of the article handling device.

FIG. 6 is a rear elevational view of the article handling device; and,

FIG. 7 is a front, right isometric view of the article handling device.

The broken lines in the drawings illustrate portions of the article handling device that form no part of the claimed design.
